(57) **CLAIM**

The ornamental design for an automobile tire tread, as shown and described.

DESCRIPTION

FIG. 1 is a front perspective view of an automobile tire showing our new design;

FIG. 2 is a front view thereof; top plan and bottom plan views are the same as the front view;

FIG. 3 is a rear view thereof;

FIG. 4 is a left side view thereof; a right side view is a mirror image of the left side view;

FIG. 5 is an enlarged fragmentary perspective view thereof, taken along lines 5—5 and in the direction of arrows in FIG. 1;

FIG. 6 is an enlarged fragmentary front view thereof, taken along lines 6—6 and in the direction of arrows in FIG. 2; and,

FIG. 7 is a fragmentary perspective reference view thereof showing a tilted surface of a block in detail.

The broken lines shown in the drawings are for illustrative purposes only and form no part of the claimed design.
